Robert E. Kelso, Jackson, Mich., assignor to Dowley
Manufacturing, Inc., Spring Arbor, Mich.

Filed Feb. 23, 1962, Ser. No. 68,931

Term of patent 14 years

(Cl. D54—13)

FIG. 3

FIG. 4

FIG. 5

FIGURE 1 is a side view of a servicing tool for universal joints embodying my new design. The opposite side of the tool has substantially the same appearance.

FIGURE 2 is an elevational edge view of one side of the servicing tool for universal joints.

FIGURE 3 is a top view of same.

FIGURES 4 and 5 are sectional views of the servicing tool for universal joints as taken, respectively, at lines 4—4 and 5—5 of FIGURE 1, looking in the direction of the arrows.

I claim:

The ornamental design for a servicing tool for universal joints, substantially as shown and described.
